TURTLE SHELL TOY

Edwin B. Tillinger, 5403 Twining Drive, Tinker Air Force
Base, Oklahoma City, Okla. 73145

Filed Nov. 25, 1970, Ser. No. 26,160

Term of patent 14 years

Int. Cl. D21—01

U.S. Cl. D34—2

FIG. 1 is a top view of a turtle shell toy showing my new design.

FIG. 2 is a bottom view of the turtle shell toy shown in FIG. 1.

FIG. 3 is an elevational view of a side of the turtle shell toy shown in FIG. 1.

FIG. 4 is an elevational view of an end of the turtle shell toy of FIG. 1.

I claim:

The ornamental design for a turtle shell toy, substantially as shown.
